UNITED STATES PATENT OFFICE.

SAMUEL S. MATTHES, OF MANSFIELD, OHIO, ASSIGNOR TO THE OHIO BRASS COMPANY, OF MANSFIELD, OHIO, A CORPORATION OF NEW JERSEY.

CONDUCTOR CLAMP AND SUPPORT.

1,373,751.

Specification of Letters Patent.

Patented Apr. 5, 1921.

Application filed October 6, 1920. Serial No. 415,192.

To all whom it may concern:

Be it known that I, SAMUEL S. MATTHES, a citizen of the United States, residing at Mansfield, in the county of Richland and 5 State of Ohio, have invented certain new and useful Improvements in Conductor Clamps and Supports, of which the following is a specification.

My invention relates to supports for conductors and particularly that type of support known as a trolley wire clamp for gripping and supporting a trolley wire from an overhead support.

My invention has for its object a device 15 which is simple, cheap, efficient and easy of installation and consists substantially in the construction, combination, location and arrangement of parts, all of which will be more fully hereinafter set forth, and 20 claimed, and illustrated in the accompanying drawing in which:—

Figure 1 is a side elevation view of my device attached to a hanger prior to its gripping the wire.

Fig. 2 is a sectional view of Fig. 1.

Fig. 3 is a side elevation view of my device secured to a hanger and trolley wire.

Fig. 4 is a sectional view of Fig. 3.

Fig. 5 is an end view in partial section.

Fig. 6 is a sectional view on line 6—6 of Fig. 2.

Fig. 7 is a side elevation view of the operating members.

Fig. 8 is a face view of the operating 35 member.

Fig. 9 is a sectional view of a modification of my device from that shown in Figs. 2 and 4.

The preferred embodiment of my invention 40 comprises a pair of clamping jaws 1—1. A supporting member 2 is provided with means for attaching to a hanger. The means shown is a screw thread 3 which is the most usual means employed, and 45 which engages a depending threaded stud on the hanger 4.

The lower end of the support member 2 is provided with inwardly projecting flanges 5 forming a slot or recess throughout the thickness of the supporting member and which is indicated by the numeral 6. The clamping jaws 1—1 are provided with outwardly projecting flanges 7 which engage with the flanges 5 thereby preventing 55 downward movement of the jaws rela-

tively to the support member 2, allowing a pivotal movement of the two jaws relatively to each other and preventing a relative rotation of the jaws and supporting member.

My device is also provided with a collar 60 8 which is free to rotate relatively to the other parts and the lower face is provided with a sloping surface on each side of the center line thereby providing two wedge shaped surfaces 10 which are adapted to 65 engage a slightly raised part 11 on each jaw.

The parts are so proportioned that when the clamp has been applied to a hanger to its limit and then backed off sufficiently to allow the entrance of a wire between the 70 jaws 1—1 and the jaws are held in engagement with the wire, the distance B will be less than the distance A, thus assuring the forcing of the jaws to firm engagement with the wire, and the collar 14 into engagement with the hanger 4.

The support member 2 is provided with means 9 to prevent the removal of the collar 8 and the disassembly of the parts after being assembled and is produced by first 80 making the member 9 in an upright position as indicated by the numeral 9¹ and after the parts have been assembled as shown, the flange 9¹ is turned over into the position shown by the numeral 9 by means 85 of a suitable tool.

The lower edge of the jaw is provided with suitable means 12 for engaging and gripping a trolley wire 13. The outer surface of the collar 8 is provided with polygonal means 90 for the application of a wrench to rotate the collar. The upper end of the collar 8 is provided with means 15 to engage the hanger 4 in case of Figs. 2 and 4, and the supporting member 2 in 95 case of Fig. 9.

In applying my device to a hanger and trolley wire the same is applied to the hanger stud as shown in Figs. 1 and 2 and by rotating the jaws which cause the support member 2 to rotate, the supporting member is drawn upwardly upon the stud. The rotation of the device is continued until the opening between the points 12 of the jaws will just permit the insertion of 100 the trolley wire. The jaws are now held in engagement with the trolley wire and it will be found that the distance B will be less than the distance A. A wrench is then applied to the polygonal surface of the 110

collar 8 and the collar rotated in the direction of the arrow C which will cause the collar 8 to be raised due to the contact of the wedge surface 10 with a projection 11 until the surface 15 of the collar engages the lower surface of the hanger 4. When this stage of the operation is reached, further rotation of the collar 8 in the direction of the arrow C will cause the jaws 1-1 10 to be moved into a strong clamping engagement with the wire 13 and the upper face of the collar 8 into strong engagement with the lower face of the hanger, as shown in Figs. 3 and 4.

15 In the modified form shown in Fig. 9, the device is rotated in the position on the hanger stud until the member 2 is in contact or nearly so with the face of the hanger and the jaws alined with the trolley wire. 20 The wire is then inserted between the jaws and the member 8 rotated thus causing the member 8 to be raised as in the case of the construction shown in Figs. 1 and 2 and until it engages the flange on the support member 2 when its movement away from the jaws will be arrested and further rotation of the member 8 will force the jaws into 25 strong engagement with the wire.

30 There are many modifications which may be made in the details of construction and which will embody the principle of operation of my device and which will be evident to those skilled in the art, and therefore I do not wish to be limited other than 35 by the following claims:

1. A wire clamp for gripping and securing a conductor to a support comprising clamping means, supporting means and rotatable operating means having a helical 40 face coating with the clamping means to move the clamping means into engagement with the conductor when rotated.

2. A wire clamp for gripping and securing a conductor to a hanger comprising 45 clamping means, supporting means to engage the hanger, operating means slidably mounted on the supporting means and adapted to engage the clamping means and the hanger and having a helical means on 50 one of its engaging faces to move the clamping means into engagement with the conductor.

3. A wire clamp secured to a hanger to grip and support a conductor comprising a 55 supporting member, clamping means, operating means mounted on the clamping means and helical means on the engaging face of one of the last two means to move the clamping means into engagement with the conductor.

60 4. A wire clamp to be secured to a hanger to grip and support a conductor comprising a supporting member, a two-part clamping means and an operating 65 member provided with a plurality of

wedges on one face, each wedge adapted to engage a part of the clamping means and move the clamping means into engagement with the conductor.

5. A wire clamp to be secured to a 70 hanger to grip and support a conductor comprising a supporting member, clamping means, operating means slidably mounted on the supporting means and adapted to engage the clamping means and hanger and 75 means on one face of the operating means to move the operating means into engagement with the hanger and the clamping means into engagement with the conductor.

6. A wire clamp to be secured to a 80 hanger to grip and support a conductor comprising a supporting member, clamping means, operating means slidably mounted on the supporting means and adapted to engage the clamping means and hanger and 85 means on the operating means to move the operating means into engagement with the hanger and the clamping means into engagement with the conductor.

7. A wire clamp to be secured to a 90 hanger to grip and support a conductor comprising clamping means to grip and hold the conductor, means to secure the clamping means to the hanger, operating means slidably and rotatably mounted and adapted to engage the clamping means and hanger, and means on one face of the operating means to move the operating means into engagement with the hanger and the clamping means into engagement with the 95 conductor when the operating means is rotated.

8. A wire clamp to be secured to a hanger to grip and support a conductor comprising 100 clamping means to grip and hold the conductor, means to secure the clamping means to the hanger, operating means slidably and rotatably mounted and adapted to engage the clamping means and hanger and means on the operating means to move the operating 105 means into engagement with the hanger and the clamping means into engagement with the conductor when the operating 110 means is rotated.

9. A wire clamp to be secured to a hanger 115 to engage and support a conductor comprising clamping means to grip and hold the conductor, means to secure the clamping means to the hanger, unitary operating 120 means slidably and rotatably mounted and adapted to engage the clamping means and helical means on the operating means to move the clamping means into engagement with the conductor when the operating 125 means is rotated.

10. A wire clamp to be secured to a hanger to engage and support a conductor comprising clamping means to grip and hold the conductor, means to secure the clamping means to the hanger, unitary operating 130

- means slidably and rotatably mounted interposed between the hanger and the clamping means to engage the hanger and move the clamping means into engagement with the conductor. 5
11. A wire clamp to be secured to a hanger to engage and support a conductor comprising a clamping means to grip and hold the conductor, means to secure the clamping means to the hanger, and a member rotatably and slidably mounted on the securing means and provided with a helical face and interposed between the hanger and clamping means, the helical face coacting with one of the other parts to move the operating means into engagement with the hanger and the clamping means into engagement with the conductor when the interposed member is rotated. 10
12. A wire clamp to be secured to a hanger to engage and support a conductor comprising clamping means to grip and hold a conductor, a supporting member for attachment to a hanger and having means to pivotally support the clamping means and an operating member rotatably and slidably mounted relatively to the supporting member to engage and move toward and away from the clamping means, and means to limit the movement of the operating member away from the clamping means and means on the operating member to move the clamping means into engagement with the conductor when the operating member is rotated. 15
13. A wire clamp to be secured to a hanger to engage and support a conductor comprising clamping means, a supporting member, rotatable operating means arranged to engage the clamping means, and means on the clamping means to engage means on the operating means adapted to move the operating means away from the conductor and against a stop, thereby moving the clamping means into engagement with the conductor. 20
14. A wire clamp for gripping and securing a conductor to a support comprising clamping means, supporting means, rotatable operating means, means to prevent the operating means moving relatively to and away from the clamping means but permitting rotation of the operating means relatively to the supporting means and means on the operating means to move the operating means into engagement with the clamping means when the operating means is rotated to move the clamping means into engagement with the conductor. 25
15. A wire clamp for gripping and securing a conductor to a hanger comprising clamping means, supporting means, a rotatable operating member mounted on the supporting means and provided with wedging means on one face engaging means on the clamping means whereby rotation of the operating member will move the clamping means into engagement with the conductor and means on the supporting means engaging the operating member to prevent the removal of the operating member. 30
16. A wire clamp to be secured to a hanger to grip and support a conductor comprising a supporting member, clamping means, an operating member rotatably mounted on the supporting member and adapted to engage the hanger and clamping means, and means on one face of the operating member engaging means on one face of the clamping means to move the operating means into engagement with the hanger and the clamping means into engagement with the conductor when the operating member is rotated. 35
17. A wire clamp to be secured to a hanger to grip and support a conductor comprising a supporting member, clamping means and an operating member rotatably mounted on the supporting member, the operating member being provided with means to engage means on the clamping means whereby a force is applied upon the clamping means in a direction substantially parallel to the axis of the supporting member, to move the clamping means into engagement with a conductor and to move the operating member in a direction substantially parallel to the axis of the supporting member, when the operating member is rotated. 40

In testimony whereof I affix my signature.
SAMUEL S. MATTHES.
